(57) **CLAIM**

The ornamental design for a lighting system suspension mounting, as shown and described.

DESCRIPTION

FIG. 1 is a perspective view of a lighting system suspension mounting showing my new design;

FIG. 2 is a first side elevational view thereof;

FIG. 3 is a second side elevational view thereof;

FIG. 4 is a third side elevational view thereof;

FIG. 5 is a fourth side elevational view thereof;

FIG. 6 is a top plan view thereof;

FIG. 7 is a bottom plan view thereof

FIG. 8 is a perspective view of a lighting system suspension mounting showing my new design;

FIG. 9 is a first side elevational view thereof;

FIG. 10 is a second side elevational view thereof;

FIG. 11 is a third side elevational view thereof;

FIG. 12 is a fourth side elevational view thereof;

FIG. 13 is a top plan view thereof; and,

FIG. 14 is a bottom plan view thereof.

The broken lines shown in the drawings are included for the purpose of illustrating elements of the lighting system suspension mounting that is configured to be hung from a surface and form no part of the claimed design.
